VERNIER DIAL FOR RADIO ADJUSTMENTS

Filed June 12, 1922

Patented Sept. 11, 1928.

1,683,845

UNITED STATES PATENT OFFICE.

ADOLPH PETELER, OF FREEPORT, NEW YORK, ASSIGNOR TO THOMAS HOWE, OF WHITE PLAINS, NEW YORK.

VERNIER DIAL FOR RADIO ADJUSTMENTS.

Application filed June 12, 1922. Serial No. 567,857.

This invention relates to indicating means whereby more observations may be made of the adjustment of radio apparatus such as variometers, condensers &c. but it may have 5 other uses.

The usual radio receiving set has a case in which apparatus is mounted and upon a panel board are placed rotatable knobs which are suitably connected with the parts 10 to be adjusted and dials or scales are provided in conjunction with the knobs whereby the positions of adjustment of the apparatus may be observed.

Ordinarily these dials are mounted in direct connection with the knob and adjusting shaft and, as for instance in the case of a variometer, the adjustment is made through a range of one-half the turn of the shaft. The dial therefore is only turned through 20 one-half of a revolution and consequently the indicating scale may only occupy one-half of the circumference of the dial and within the space permissible the dial must be made of such size that the graduations 25 are quite small and do not permit of a nice observation and adjustment. For this reason the best results are not uniformly obtained because it is difficult to accurately adjust the parts to the best position.

It is the main object of the present invention to provide means for more accurately observing the adjustment of the parts and to this end I provide a vernier dial which is compact and readily applicable to the dials 30 now in use. A further object of the invention is to provide means whereby the vernier may be readily thrown into and out of operative relation with the main dial.

Other and ancillary objects of the invention will appear hereinafter.

In the accompanying drawings which illustrate the invention—

Fig. 1 is a front elevation of a dial and vernier;

Fig. 2 is a bottom plan view of the vernier structure on an enlarged scale;

Fig. 3 is a view showing a section on the line 3—3 of Fig. 2;

Fig. 4 is a section on the line 4—4 of

Fig. 3;

Fig. 5 is a front elevation of a portion of a modified form of vernier gearing; and

Fig. 6 is a section on the line 6—6 of Fig. 5.

Referring to the drawings the usual panel

1 has rotatably mounted within it the shaft 2 which is in connection with the part to be adjusted. Fixed to this shaft is the usual dial 3 and the knob 4 for effecting the adjustment. 60

The vernier apparatus comprises a housing 5 secured to the panel by means of bolts or screws 6. Rotatably mounted in the housing is a spindle or shaft 7 on which is mounted the vernier 8. Also fixed to the 65 shaft 7 is a knurled hub 9 adapted to engage with a rubber-faced wheel 10, the rubber face being yielding but sufficiently firm so as to form a driving engagement with the hub 9. The rubber face is also adapted to 70 be pressed against the rim of the main dial 3 so as to form a frictional driving connection therewith. The wheel 10 is rotatably mounted in one arm of the double bell crank lever 11 which is rotatably mounted 75 upon the shaft 7.

Another arm of the bell crank lever as shown has secured to it one end of a spring 12, the other end of the spring being secured to a pin 13 in the housing. This 80 spring tends to throw the wheel or gear 10 into driving engagement with the rim of the dial 3.

Another arm 14 of the bell crank lever extends through a slot 15 in the bottom of the housing 5 so that its extremity at the exterior of the casing can be grasped by the fingers and pushed in one direction or the other to move the wheel 10 into and out of engagement with the rim of the 90 main dial. To draw this wheel out of engagement the arm 11 will be moved towards the left (see Fig. 3) against the tension of the spring 12 and may be locked in the disengaged position by pressing the arm 11 95 into the recess or notch 16 opening into the slot 15. On releasing the arm from the notch the spring will throw the rubber covered wheel 10 against the rim of the tire.

Referring now to Figs. 5 and 6, gears 17 100 and 18 which may be substituted for the members 9 and 10 of the preceding figures, are rotatably mounted in a smaller bell crank as shown, when the tooth engagement as shown in Fig. 5 will replace the engagement of the rubber of the wheel 10 with the knurled hub 9. The gear 18 has formed upon it a post 19 having the rubber covering 20 adapted to be pressed against the rim 105 of the dial. 110

It will be observed that the vernier will rotate in the same direction as the main dial which is of advantage in observing the indications. The driving connections between the vernier and the main dial may be made if desired, so that the interpolated readings of the vernier may be made of the desired size.

It will be seen that the vernier structure 10 may be applied to the standard form of adjustment indicator of radio receiving sets by simply securing the housing 5 and its carried parts to the panel in proper relation to the usual dial and that the vernier attachments 15 may be made in a complete unitary structure requiring no further skill.

While the invention has been illustrated in what is considered its best application it 20 may have other embodiments without departing from its spirit and is not therefore limited to the structure shown in the drawings.

What I claim is:

1. The combination with a main indicator 25 of a vernier attachment comprising in combination a housing, a shaft rotatably mounted therein, a vernier indicator secured to said shaft upon the exterior of said housing, a lever within the housing pivoted upon said shaft, a driving wheel pivoted in said lever and engaging with said shaft to drive the same, said driving wheel being adapted to be moved into and out of driving relation with the main indicator by turning said lever upon its pivot, a spring tending to force said driving wheel against said main indicator and means for holding said driving wheel out of engagement with said main indicator against the bias of said spring.
2. A vernier control device for radio apparatus of the character described, including a driving wheel having a peripheral driving face of soft resilient material of comparatively large diameter, and a com-

paratively small manually rotatable driving shaft of comparatively hard material rotatably engaging the soft wheel face.

3. A vernier control for radio apparatus of the character described, comprising a rotatable dial having a comparatively large peripheral surface, a wheel having a friction peripheral edge engaging the dial surface, and a manually rotatable shaft of comparatively small diameter for engaging and rotating the wheel to rotate the dial.

4. A vernier control for radio apparatus of the character described, comprising a rotatable dial having a comparatively large peripheral surface, a wheel having a friction peripheral edge engaging the dial surface, and a manually rotatable shaft of comparatively small diameter for engaging and rotating the wheel to rotate the dial, said dial and shaft being movable in the same rotary direction.

5. A vernier control for radio apparatus of the character described including a main operating shaft, a manually rotatable shaft having a hard driving face of comparatively small diameter, and a wheel intermediate the main and auxiliary shafts having a comparatively soft peripheral face engaged by the auxiliary shaft when rotated to rotate the main shaft.

6. A freely rotatable dial, a bell crank 75 lever, a roller journaled in one of the arms and movable into and out of engagement with the dial as the lever is moved about its pivot, and a knob like device connected with the roller for rotating the latter with respect 80 to the lever to rotate the dial, the said roller having a surface of slightly yielding material to frictionally engage the periphery of the dial.

In testimony whereof I have signed this 85 specification this 10th day of June, 1922.

ADOLPH PETELER.
